CLAIM

The ornamental design for an electro-optic digital display for a timepiece, as shown and described.

DESCRIPTION

FIG. 1 is a front elevational view of an electro-optic digital display for a timepiece showing my new design in an non-energized condition;

FIG. 2 is a top plan view thereof;

FIG. 3 is a right side elevational view thereof, the left side being a mirror image thereto;

FIG. 4 is a rear elevational view thereof;

FIG. 5 is a front elevational view thereof in a representative energized display of 12:45 p.m. and 30 seconds on Tuesday;

FIG. 6 is a front elevational view thereof in a representative energized display of the alarm set at 6:30 p.m. on Friday;

FIG. 7 is a front elevational view thereof in a representative energized display of Tuesday, Apr. 6th.
